UNITED STATES PATENT OFFICE.

WILLIAM REA AND GEORGE E. FERGUSON, OF NEW YORK, N. Y., ASSIGNEES TO PYRENE
MANUFACTURING COMPANY, A CORPORATION OF DELAWARE.

PORABLE FIRE-EXTINGUISHER.

1,184,019.

Specification of Letters Patent.

Patented May 23, 1916.

Application filed March 3, 1915, Serial No. 11,716. Renewed November 11, 1915. Serial No. 60,973.

To all whom it may concern:

Be it known that we, WILLIAM REA, having declared his intention to become a citizen of the United States by taking out his first papers, and residing in the city of New York, Bronx county, and State of New York, and GEORGE E. FERGUSON, a citizen of the United States, and resident of the city, county, and State of New York, have invented certain new and useful Improvements in Portable Fire-Extinguishers, of which the following is a specification.

This invention relates to a portable fire extinguisher in which the fire-extinguishing liquid is expelled from the container by means of pressure.

Experiments have been made on various liquids, using air pressure to expel the contents of the extinguisher, but in all cases where compressed air or gas is held in a metal container to be used at some future time as an energy the results have been unsatisfactory. The most satisfactory method found to expel liquids from a container is by using a chemical which when acted upon by certain reagents will liberate a gas.

Extinguishers now in use are of the soda and acid type, in which the apparatus consists of a metal container having a liquid exit at the top and also a cage for holding a bottle of acid (generally sulfuric acid). To charge this apparatus, two and one-half gallons of a water solution of bicarbonate of soda is poured into the container; a bottle of sulfuric acid is next placed in a cage (the bottle being supplied with a very loose fitting stopper) and the cage is then set in position and the lid or top casting screwed into place. To operate the extinguisher, the container is turned bottom side up, which causes the cork or stopper to drop from the acid bottle and permits the action of the acid upon the soda solution. This action is very simple—sulfuric acid acting upon bicarbonate of soda produces carbon dioxide gas, sodium sulfate, and water. The gas thus produced passes to the bottom of the extinguisher (which is now on top during the ejection of the liquid) and forces the water solution, which now consists of the dissolved sodium sulfate and unacted upon bicarbonate of soda, from the extinguisher. This extinguisher is limited in its use to soluble carbonates and bicarbonates in water

solution. It becomes necessary, therefore, in order to utilize substances which are insoluble in a water solution for generating the gas, or which would react if mixed with soluble carbonates in water solution, to provide an extinguisher having two compartments, one for the generation of the gas and the other for holding the extinguishing fluid. For the reasons stated, it is essential to prevent the contents of the gas generating chamber from coming in contact with the liquid in the second compartment and, at the same time, permit the gas which is generated to pass from the gas generating chamber to the extinguishing liquid compartment. Certain mechanical features are necessary to accomplish this purpose, which features form the subject of this invention.

After the contents of the extinguisher have been expelled, it is essential to prevent any reactionary products in the gas generating chamber passing to the compartment which contained the fire extinguishing compound, because in refilling the extinguisher, a reaction will take place between the liquid in the fire-extinguishing liquid compartment and the reactionary products of the gas generating chamber which have passed into the lower compartment when the extinguisher has been righted again after the charge has been expelled.

To prevent this, is another object of this invention.

In the drawings we have illustrated the invention by a sectional side elevation of an extinguisher embodying the features hereinafter described.

In the drawings 18 is the compartment for holding the fire extinguishing fluid and is separated from the gas generating chamber 17 by the partition or wall 6. This wall 6 is provided with a depression 19 which may be in the form of a cup attached thereto, which has for its purpose the holding of the acid container 4 in position and also serving as a funnel for filling the compartment 18 with the fire extinguishing fluid. At the lower extremity of the depression 19 is attached a pipe 13 which extends from the base of 19 to a point near the bottom of the compartment 18 and has for its purpose the conducting of the gas which is generated in the compartment 17 to the compartment 18. At the point where the pipe 13 joins the de-

pression 19 there is fitted a screen 9 to prevent any solid substance passing into the tube 13 during the process of filling the extinguisher. Just below this point and in the 5 pipe 13 is placed a one-way ball valve which permits gas and liquid to flow through the pipe 13 from the compartment 17 to the compartment 18 but which prevents the passage of liquid from the chamber 18 back into the chamber 17. This ball valve consists of 10 a ball 10, a pin 12 to prevent the ball falling through the pipe 13 and a seat 11 for the ball, substantially as shown.

An extension 5 of the cup 19 extends above 15 the separating wall 6 and acts as a baffle, preventing the products of the reactions in the gas generating chamber 17 from passing out of this chamber into the container 18 when the extinguisher is righted again after 20 the liquid has been expelled. An elbow 7 attached to the container 18 has attached thereto a hose and nozzle 14 for directing the stream of fire extinguishing liquid.

The acid container 4 fits loosely in the 25 cup 19 and rests on the jugs 8 attached to bottom of the cup 19, which permits the gas generated in the chamber 17 to pass to the chamber 18 through the pipe 13. The acid container 4 is fitted with a loosely fitting stopper 3. A cover or top casting 1 screws on to the threaded casting 16. A screen 2 in the form of a perforated cylinder is attached to the under side of the cover 1 and, when the top casting 1 is in place, 30 rests against the acid container 4, holding the same in position. The screen 2 is larger in diameter than the loose fitting stopper 3 which it surrounds. When the extinguisher is inverted the acid container 4 rests against the screen 2 and simultaneously the loose fitting stopper 3 drops away from the acid container 4. This permits the acid to flow from the acid container into the carbonate contained in the chamber 17, generating the 45 gas which is forced into the chamber 18 through the pipe 13, thereby forcing the liquid from the chamber 18 through the elbow 7 and hose and nozzle 14.

What we claim is—

50 1. In a fire extinguisher, in combination, a compartment for the fire extinguishing fluid, a gas generating chamber separated from said compartment by a partition wall, a pipe providing a communication between said gas chamber and fluid compartment, an acid container positioned in said gas chamber, and a screen positioned between said acid container and the cover of the extinguisher for holding said container in position.

55 2. In a fire extinguisher, in combination, a compartment for the fire extinguishing fluid, a gas generating chamber separated from said compartment by a partition wall, provided with a depression in which an acid

container is positioned, an acid container positioned in said depression in said gas chamber, a pipe providing a communication between said gas chamber and fluid compartment, and a screen positioned between said acid container and the cover of the extinguisher for holding said container in position. 70

3: In a fire extinguisher, in combination, a compartment for the fire extinguishing fluid, a gas generating chamber separated from said compartment by a partition wall, communicating means through said wall between said gas chamber and fluid compartment, an extension mounted on said wall surrounding said communicating means adapted to prevent the products of reaction in said gas chamber from passing therefrom, an acid container positioned in said gas chamber, and a screen positioned between said acid container and the cover of the extinguisher for holding said container in position. 75

4. In a fire extinguisher, in combination, a compartment for the fire extinguishing fluid, a gas generating chamber separated from said compartment by a partition wall, communicating means through said wall between said gas chamber and fluid compartment, a cup shaped member attached to said wall and at the bottom of which said communicating means is positioned, said partition wall and cup-shaped member being adapted to prevent the products of reaction in said gas chamber from passing therefrom, an acid container positioned in said gas chamber, and a screen positioned between said acid container and the cover of the extinguisher for holding said container in position. 80

5. In a fire extinguisher, in combination, a compartment for the fire extinguishing fluid, a gas generating chamber separated from said compartment by a partition wall, communicating means through said wall between said gas chamber and fluid compartment, a cup shaped member attached to said wall extending on either side thereof and at the bottom of which said communicating means is positioned, said partition wall and cup-shaped member being adapted to prevent the products of reaction in said gas chamber from passing therefrom, an acid container positioned in said gas chamber, and a screen positioned between said acid container and the cover of the extinguisher for holding said container in position. 85

6. In a fire extinguisher, in combination, a compartment for the fire extinguishing fluid, a gas generating chamber separated from said compartment by a partition wall, communicating means through said wall between said gas chamber and fluid compartment, a cup shaped member attached to said wall and at the bottom of which said com-

- municating means is positioned, said partition wall and cup-shaped member being adapted to prevent the products of reaction in said gas chamber from passing therefrom, an acid container positioned in said cup shaped member, and a screen positioned between said acid container and the cover of the extinguisher for holding said container in position.
- 19 7. In a fire extinguisher, in combination, a compartment for the fire extinguishing fluid, a gas generating chamber separated from said compartment by a partition wall, said partition wall having attached thereto 45 a cup shaped member provided with a pipe extending from the bottom of said cup shaped member to the opposite side of said fluid compartment, the sides of said cup shaped member forming a baffle preventing the products of reaction in said gas chamber from passing into said communicating means, and an acid container positioned in said cup shaped member.
- 15 8. In a fire extinguisher, in combination, a compartment for the fire extinguishing fluid, a gas generating chamber separated from said compartment by a partition wall, said partition wall having attached thereto 50 a cup shaped member extending on either side thereof and provided with communicating means extending from the bottom thereof and forming a communication from said gas chamber to said fluid compartment, the sides of said cup shaped member forming a baffle preventing the products of reaction in said gas chamber from passing into said communicating means, and an acid container positioned in said cup shaped member.
- 20 9. In a fire extinguisher, in combination, a compartment for the fire extinguishing fluid, a gas generating chamber separated from said compartment by a partition wall, said partition wall having attached thereto 55 a cup shaped member provided with a pipe extending from the bottom of said cup shaped member to the opposite side of said fluid compartment, the sides of said cup shaped member forming a baffle preventing the products of reaction in said gas chamber from passing into said communicating means, and an acid container positioned in said cup shaped member.
- 25 10. In a fire extinguisher, in combination, a compartment for the fire extinguishing fluid, a gas generating chamber separated from said compartment by a partition wall, said partition wall having attached thereto 60 a cup shaped member provided with a pipe provided with a valve and extending from the bottom of said cup shaped member to the opposite side of said fluid compartment, the sides of said cup shaped member forming a baffle preventing the products of reaction in said gas chamber from passing into said communicating means, and an acid container positioned in said cup shaped member.
- 30 11. In a fire extinguisher, in combination, a compartment for the fire extinguishing fluid, a gas generating chamber separated from said compartment by a partition wall, said partition wall having attached thereto 65 a cup shaped member provided with a pipe extending from the bottom of said cup shaped member to the opposite side of said fluid compartment, the sides of said cup shaped member forming a baffle preventing the products of reaction in said gas chamber from passing into said communicating means, and an acid container positioned in said cup shaped member.
- 35 12. In a fire extinguisher, in combination, a compartment for the fire extinguishing fluid, a gas generating chamber separated from said compartment by a partition wall, said partition wall having attached thereto 70 a cup shaped member provided with a pipe extending from the bottom of said cup shaped member to the opposite side of said fluid compartment, the sides of said cup shaped member forming a baffle preventing the products of reaction in said gas chamber from passing into said communicating means, and an acid container positioned in said cup shaped member.

Signed at the city, county and State of 70
New York, this 25th day of February, 1915.
